UNITED STATES PATENT OFFICE.

ROBERT H. STEVENSON, JR., OF WESTERN SPRINGS, ILLINOIS.

ALARM ATTACHMENT FOR INCUBATORS.

SPECIFICATION forming part of Letters Patent No. 695,245, dated March 11, 1902.

Application filed May 4, 1901. Serial No. 58,796. (No model.)

To all whom it may concern:

Be it known that I, ROBERT H. STEVENSON, Jr., a citizen of the United States, residing at Western Springs, in the county of Cook and State of Illinois, have invented new and useful Improvements in Alarm Attachments for Incubators, of which the following is a specification.

This invention relates to incubators, and has for its object to provide a simple electric alarm in the nature of an attachment for incubators of ordinary construction and adapted to indicate audibly whenever the temperature rises or falls to an extent which will be dangerous or injurious to the contents of the incubator.

Other objects of the invention will appear in the course of the subjoined description.

The invention consists in an alarm attachment for incubators embodying certain novel features and details of construction and arrangement of parts, as hereinafter fully described, illustrated, and claimed.

In the accompanying drawings, Figure 1 is a side elevation of an incubator, showing an electrical alarm attachment applied thereto. Fig. 2 is a detail perspective view of the block, forming part of the attachment and carrying the contact-points and terminal conductors.

Similar numerals of reference designate corresponding parts in both figures of the drawings.

Referring to the drawings, 1 designates the body of an ordinary incubator; 2, the heater; 3, the chimney or flue which communicates with the interior of the incubator-body, and 4 the damper-arm or balance-rod, which is mounted at a point intermediate its ends upon a fulcrum-post 5 and provided at one end with a damper 6 and at its opposite end with a counterbalance-weight 7, the said parts being of the ordinary construction and arrangement.

In carrying out the present invention I provide a suitable block or base 8, containing a pair of terminal conductors 9 in the form of rods or wires bent into substantially U shape, as indicated in Fig. 2, and having their extremities projecting outside of the block and bent upward, as shown at 10, the said extremities being provided with suitable con-

tact-points 11 and 12, arranged in substantially the same horizontal plane and in pairs at or near each end of the block 8. Circuit-wires 13 connect the terminals 9, respectively, with a battery 14 and alarm-bell 15, which are for convenience mounted on the top of the incubator-body, as illustrated in Fig. 1.

The balance-rod 4 is provided with a pair of circuit-closers or bridges 16 in the form of metal plates secured to the lower side of the balance-rod at suitable points to come in contact with the contact-points 11 and 12 as the balance-rod is tilted in one direction or the other.

In operation as the temperature rises or falls to a point which is ordinarily dangerous or injurious to the eggs the balance-rod 4, influenced by the usual thermostat, (not shown,) will tilt in one direction or the other, thereby bringing one of the contact-makers or bridges 16 into engagement with the pair of contacts 12 or the pair of contacts 11, according to the direction in which the balance-rod tilts. Under either extreme movement of the balance-rod 4 it will therefore be apparent that the circuit containing the alarm-bell will be closed, thereby audibly indicating that the heater of the incubator needs attention. By the arrangement disclosed the alarm will be sounded when the temperature rises too high or falls too low or in case the flame of the heater should be accidentally blown out or otherwise interfered with.

It will be understood that the alarm attachment hereinabove described is applicable to incubators already on the market and in use and that the said attachment does not necessarily form a part of the original construction of the incubator. It will also be understood that the device is susceptible of changes in the form, proportion, and minor details of construction, which may be accordingly resorted to without departing from the principle or sacrificing any of the advantages of the invention.

Having thus fully described my invention, what I claim as new, and desire to secure by Letters Patent, is—

In an alarm attachment for incubators, the combination with the balance-rod of the thermostat, said rod being arranged exteriorly of

the incubator-casing and fulcrumed thereon intermediate its ends, of a plurality of circuit-closers carried by said rod at opposite sides of the fulcrum, two sets of contact-points 5 arranged at opposite sides of the fulcrum of the balance-rod in the path of movement of the circuit-closers and in an electric alarm-circuit, and an attaching-block applied to the incubator-casing and forming a support for

both sets of contact-plates and the electrical conductors therefor.

In testimony whereof I affix my signature in presence of two witnesses.

ROBERT H. STEVENSON, JR.
